TARGET

William F. Winning and Carl Keyser,
Braddock, Pa.

Application August 14, 1933, Serial No. 685,115

5 Claims. (Cl. 124—15)

Our invention relates to targets and more particularly to a target wherein a visual means is provided for indicating when the target is struck by a projectile and it consists in the constructions, arrangements and combinations herein described and claimed.

It is an object of the invention to provide a target embodying a plurality of "bulls-eyes" each of which are associated with a visual indicator 10 which will be displayed upon striking of the "bulls-eyes" by a projectile, and further provides a novel means for retaining the bulls-eyes in operative position within the target proper, yet quickly releasable upon striking thereof.

15 It is a still further object of the invention to provide a target of the character set forth, which will be of simple construction, and embodying visual indicators of comical caricatures whereby interest and pleasure may be afforded children as well as adults.

Additional objects, advantages and features of invention will be apparent from the following description considered in conjunction with the accompanying drawing, wherein

25 Figure 1 is a front elevation of our target, one of the comical caricatures or indicators being shown in dotted lines.

Figure 2 is an enlarged sectional view on the line 2—2 of Figure 1.

30 Figure 3 is a fragmentary rear elevation of one of the indicators in set position.

Figure 4 is a cross section on the line 4—4 of Figure 3.

35 Figure 5 is a view similar to Figure 3 illustrating the indicator in projected position.

Figure 6 is a sectional view on the line 6—6 of Figure 5.

There is illustrated a target 10 which may be of any desired construction, but in the present instance, we have shown the targets as having a

40 semi-circular formation in plan view, the lower straight edge 11 constituting a footing for the target. Upon the rear face of the target 10, and spaced in vertical relation adjacent each side of

45 the target there are ears 12. The ears 12 afford a bearing for respective leg members 13, as clearly shown in Figure 2. It should be noted that the leg members 13 provide ample support for

the target when extended at right angles to the target, and that the leg members are swingably mounted within the bearings 12, so that the legs

50 may be swung into a plane parallel with the target, which would be the position of the legs when arranging the target for storage or shipment.

Within a central portion of the target 10, there are provided a series of circular apertures 14, spaced in semi-circular formation, concentric with edge of the target 10. Within each of the apertures 14 there is releasably retained a respective bulls-eye 15.

The bulls-eyes 15 are of course the object at which a projectile is to be directed, and in order to give a visual indication of striking the bulls-eye, each of the bulls-eyes has associated therewith an indicator 16, which in the present instance is shown as a comical caricature, although the indicator may be of various configurations and represent different persons, objects, or may even embody numerals, so that it is possible for a group of players to enter into a contest to determine who can shoot the highest score, which would be done by a totaling of the various numerals displayed by the shots of each respective contestant.

55 The indicators 16 are adapted to be projected radially outward from the center of the target 10 beyond the outer edge thereof in order that they will be clearly displayed. The indicators 16 are identical in construction and therefore a description of but one will be dealt with herein, and attention is now directed particularly to Figures 3 to 6 of the drawing.

70 Upon the rear face of the target 10 there are mounted guide channels 17, each being aligned centrally with respective apertures 14. The channels 17 are extended radially from the apertures, preferably, although this positioning of the channels may be varied to suit conditions. The channels 17 are formed from light sheet metal, bent into substantially U-shape, as seen in end elevation, the free edges stopping short of each other to define a slot 18. Within each channel 17, a strip 19 is slidably mounted, the outer end of the strip supporting the indicator 16. Cover 75 members 20 are mounted upon the back of the target, there being one for each indicator 16 and as will be understood houses the indicator in one position of its movement and likewise affords support for the indicator during its sliding movements. The upper edge of the channels 17 are cut away as at 21 to permit the indicators to move into their respective covers.

80 That end of the channels 17 disposed toward the center of the target, stops short of the apertures 14 a suitable distance and terminates in opposed ears 22. Between the ears 22 there is mounted a trigger 23 swingably secured by a pintle 24. The trigger 23 is of a length to extend beyond the aperture 14 a short distance and 85

90 95 100 105 110

slightly offset from the medial portion of the aperture a bulls-eye 15 is fixed by a rivet or nail 25. It will be obvious from consideration of Figure 4 that by having the bulls-eye slightly offset 5 with respect to the aperture 14, a minute frictional contact between the bulls-eye and aperture is established, thereby maintaining the bulls-eye in seated position within the aperture, yet readily releasable when struck by a projectile, as will be 10 more fully explained hereinafter.

In order that the bulls-eye 15 may be quickly and positively withdrawn from the aperture 14 when struck by a projectile, a spring 26 is mounted upon the pintle 24, one arm 27 of which bears 15 upon the target 10, while the other arm 28 is fixed to the trigger 23, as at 29.

The indicator 16 is adapted to be moved outwardly beyond the target 10 simultaneously with the release of the bulls-eye 15, and this is effected 20 through a link 30, the link 30 being connected to the trigger 23 by an eyelet 31, adjacent the extremity of the trigger, and to the strip 19 by an eyelet 32.

In use, a projectile is directed at a chosen bulls-eye and if the aim is accurate will be struck, thereby forcing the bulls-eye from its frictional contact with its aperture 14, whereupon the spring 26 will swing the trigger outwardly. Upon outward movement of the trigger the strip 19 will be 30 given an outward sliding movement by virtue of the link 30. The movement of the strip 19 must be sufficient to display the comical caricature or indicator beyond the target where it may be readily seen by the contestants. In order to reset the bulls-eye, it is only necessary to swing the trigger so as to again place the bulls-eye in its aperture 14, which movement will of course draw the indicator into the housing 20.

While we have shown and described a preferred 40 construction of our invention, we do not limit ourselves to the exact structure shown and described, and consider as our own, all such modifications as fairly fall within the scope of the appended claims.

45 We claim:—

1. A target comprising a plurality of apertures, a guide means carried by said target and associated with each respective aperture, said guide means extending from a point adjacent each respective aperture to the outer edge of said target, an indicator member slidable within said guide means, a bulls-eye frictionally retained 50 within each respective aperture and swingably mounted with respect to said target, a link member connecting said bulls-eye and said indicator

member, and spring means for projecting said indicator member upon release of respective bulls-eyes.

2. A target comprising a plurality of apertures, a guide means carried by said target and associated with each respective aperture, said guide means extending from a point adjacent each respective aperture to the outer edge of said target, an indicator member slidable within said guide means, a trigger member hingedly connected to said guide means, a bulls-eye connected to said trigger, and adapted to frictionally contact its respective aperture when seated therein, spring means carried by said trigger and tending to unseat said bulls-eye, and a link member connected between said trigger and said indicator member. 80 85 90

3. A target comprising a plurality of apertures, a guide means carried by said target and associated with each respective aperture, said guide means extending from a point adjacent each respective aperture to the outer edge of said target, an indicator member slidable within said guide means, a trigger member hingedly connected to said guide means, a bulls-eye connected to said trigger, and offset slightly with respect to its aperture whereby to frictionally retain said bulls-eye, spring means carried by said trigger and tending to unseat said bulls-eye, and a link member connected between said trigger and said indicator member. 95 100 105

4. A target having an aperture, a guide means carried by said target and associated with the aperture and extending to a point adjacent the outer edge of the target, an indicator member slidable within said guide means, a bulls-eye frictionally retained within the aperture and swingably mounted with respect to said target, connecting means between the bulls-eye and the indicator member, and means for projecting the indicator member beyond the target upon release of the bulls-eye. 110 115

5. A target having an aperture, a guide means carried by the target and extending from the aperture to the outer edge of the target, an indicator member slidable within said guide means, a bulls-eye frictionally retained within the aperture and swingably mounted with respect to said target, a link member connecting the bulls-eye and the indicator member, and spring means for projecting said indicator member upon release of the bulls-eye. 120 125 130
